UNITED STATES PATENT OFFICE.

KEGHAM BALIKJIAN, OF NEWARK, NEW JERSEY.

ARTICLE OF FURNITURE.

Application filed August 13, 1924. Serial No. 731,768.

To all whom it may concern:

Be it known that I, KEGHAM BALIKJIAN, a citizen of the United States of America, and a resident of Newark, in the county of 5 **Essex** and State of New Jersey, have invented a new and Improved Article of Furniture, of which the following is a description.

My invention relates to sofas as well as 10 to chairs and upholstered articles of furniture, and the invention particularly relates to the means for supporting the springs in the upholstery. It is well known that springs in upholstered furniture when sustained by an ordinary arrangement of webbing strips result in the breaking down of the upholstery owing to the lack of strength and durability in the webbing assemblage.

The general object of my invention is to 20 provide a novel web assemblage possessing increased strength, ample to sustain the springs for an indefinite period without danger of the upholstery breaking down due to the breaking of the webbing.

25 My invention provides a construction of an article of furniture that permits of the embodiment of a webbing assemblage comprising either two series of crossed webbing strips to support the springs or a single 30 series of webbing strips so positioned as to afford increased resistance to the tendency of the springs and the strains of use to disrupt the webbing.

Reference is to be had to the accompanying 35 drawings forming a part of this specification, it being understood that the drawings are merely illustrative of one example of the invention.

Figure 1 is a front view of the upper part 40 of a two-part sofa or settee;

Figure 2 is a similar view of a stool or 45 lower part of said article;

Figure 3 is a transverse vertical section through the article of furniture with the 50 parts assembled.

In carrying out my invention in practice as for example in a sofa or like article, a stool section or lower portion designated generally by the numeral 10 is provided, 55 said stool portion including a top frame 11 here shown as rectangular and suitable legs 12. To the top surface of the frame 11 I apply longitudinal strips of webbing 13 and

transverse strips 14 arranged after the usual manner in basket pattern. The ends of the 55 webbing are secured to the members of the frame 11 by tacks 15.

The upper section of the article of furniture designated generally by the numeral 16 is here shown as in the form to constitute 60 the article a settee, said upper section having a back and arm rests. The upper section 16 includes a frame 17 usually rectangular. Advantageously, to the frame 17 at the under side of the same, in the preferred 65 form of my invention, I apply longitudinal webbing strips 18 and transverse web strips 19 made into basket pattern as usual. It will be observed that the article now embodies in its respective sections two series of 70 crossed webbing strips the one at the top surface of the stool 10 and the other on the under surface of the frame 17 of the upper section.

When the sections 10 and 16 are assembled as in Figure 3, it will be seen that the two series of strips are disposed one upon the other to reinforce each other. The result is that a support of great strength is provided for the upholstery springs 20 of 80 the seat, as will be clear from Figure 3 where it will be seen that beneath each spring are four crossing strips of webbing.

A further advantage of the described arrangement of webbing strips is that both 85 the strips on the stool 10 and the strips on the upper section 16 are clamped at their ends between the frames 11 and 17, the arrangement serving to resist the liability of the strips being torn from their connection 90 with the respective frames under the strains to which the strips are subjected when the article of furniture is in use.

As will readily be understood any suitable 95 connection may be provided between the frames 11 and 17 to prevent displacement thereof. As expedients for the purpose I have shown in the illustrated example hinges 21 connecting the frames at the back and in addition have indicated tenons 22 depending from the frame 17 and received in mortises 23 in the stool or lower section 10.

I would state in conclusion that while the 105 illustrated example constitutes a practical embodiment of my invention, I do not limit

myself strictly to the exact details herein illustrated, since, manifestly, the same can be considerably varied without departure from the spirit of the invention as defined in the appended claims.

Having thus described my invention, I claim:

1. An article of furniture including separate upper and lower sections each comprising a frame, webbing on the upper surface of the lower frame and on the under side of the upper frame, the upper frame being imposed on the lower frame so that the ends of

the webbing are clamped between the frames. 15

2. In an article of furniture, upper and lower frames, and spring supporting webbing on each of said frames and imposed one upon the other.

3. In an article of furniture, upper and 20 lower frames, and spring supporting webbing on each of said frames and imposed one upon the other; together with means uniting said frames together.

KEGHAM BALIKJIAN.
